CLAIM

The ornamental design for a grasping mat, as shown and described.

DESCRIPTION

FIG. 1 is a top front perspective view of a grasping mat, according to the present invention;

FIG. 2 is a top plan view of the grasping mat of FIG. 1;

FIG. 3 is a left side elevation view of the grasping mat of FIG. 1;

FIG. 4 is a left side perspective view of the grasping mat of FIG. 1;

FIG. 5 is a ride side elevation view of the grasping mat of FIG. 1;

FIG. 6 is a right side perspective view of the grasping mat of FIG. 1;

FIG. 7 is front elevation view of the grasping mat of FIG. 1;

FIG. 8 is a rear elevation view of the grasping mat of FIG. 1;

FIG. 9 is a bottom perspective view of the grasping mat of FIG. 1;

FIG. 10 is a bottom plan view of the grasping mat of FIG. 1;

FIG. 11 is a top right front perspective view of the grasping mat of FIG. 1; and,

FIG. 12 is a top left side perspective view of the grasping mat of FIG. 1.

Broken lines, where present, illustrate portions of the grasping mat that form no part of the claimed design.

1 Claim, 7 Drawing Sheets
